(57) **CLAIM**

The ornamental design for a doll, as shown and described.

DESCRIPTION

FIG. 1 is a perspective front view of a doll showing my new
design;

FIG. 2 is a left side view thereof;

FIG. 3 is a right side view thereof;

FIG. 4 is a rear view thereof; and,

FIG. 5 is a top plan view thereof.

The broken lines showing a skirt are for illustrative purposes
only and do not form part of the claimed design. All of the
other broken lines on the doll represent stitching.
